Fig. 5.

A technical line drawing of a mechanical assembly. It features a central circular component with a vertical slot, labeled '26'. A horizontal beam extends from the right side of this component, labeled '27'. A vertical chain or cable is attached to the top of the beam, labeled '29'. A horizontal chain or cable is attached to the bottom of the beam, labeled '30'. The assembly is mounted on a base, with a vertical rod labeled '28' extending downwards from the base. The entire assembly is shown in perspective, with various parts labeled with numbers.

UNITED STATES PATENT OFFICE.

FRANCIS J. DOYLE, OF CHICAGO, ILLINOIS.

VERTICAL-WATER-TUBE BOILER.

1,091,736.

Specification of Letters Patent. Patented Mar. 31, 1914.

Application filed May 10, 1910. Serial No. 560,407.

To all whom it may concern:

Be it known that I, FRANCIS J. DOYLE, a citizen of the United States, residing in the city of Chicago, county of Cook, and State of Illinois, have invented certain new and useful Improvements in Vertical - Water-Tube Boilers, of which the following is a specification.

This invention relates to improvements in vertical water tube boilers and has among its salient objects to provide a construction in which the fire chamber is substantially filled with a relatively large number of vertical fire tubes extending circumferentially of the fire chamber and communicating at either end with water legs; to provide a construction in which the fire chamber is not only provided with vertical water tubes extending therethrough, but is substantially surrounded or inclosed by a boiler which takes the form of the water legs; to provide a construction in which the fuel is distilled instead of being burned directly and the distilled gases ignited and oxidized while within the fire zones; to provide a construction in which any substantial pronounced induced draft through the fire chamber is substantially eliminated and the air introduced by suitable pipes or other means to various points within the fire zones; to provide a construction which secures a maximum water heating surface, whereby substantially the entire heat units generated come directly into contact with the part of the boiler surface; to provide a construction in which a major portion of the heat units generated are effectively utilized in raising the temperature of the water, instead of being drawn out through the stack or chimney, as in present constructions; to provide a construction which can be readily and economically manufactured and which is devoid of any complicated or delicate mechanisms; and in general to provide an improved construction of the character referred to.

My invention consists in the matters hereinafter described and more particularly pointed out in the appended claim.

In the drawings Figure 1 is a vertical sectional view of my invention with parts shown in side elevation; Fig. 2 is a horizontal sectional view taken substantially on line

2-2 of Fig. 1 and looking in the direction of the arrows; Fig. 3 is a view similar to Fig. 2, but showing a somewhat modified construction; Figs. 4 and 5 are detail views showing the manner of controlling the draft through the stack.

Referring to the drawings, 1 designates as a whole the ash pit, 2 the grate, 3 the fire box, the outer side wall of which is formed by a circumferentially extending water leg, 4 the inner and outer walls, 5 and 6, which are secured together by suitable staybolts or braces 7, and are united at their lower ends by an end-closure member 8. The lower end of this water leg terminates in a flange 9, which is seated in an annular channel 10, extending around the outer edge of the grate 2. The inner wall of the fire chamber is formed by a cylindrical water leg 11 closed at its lower end, as shown at 12 and open at its upper end, as shown at 13. This water leg 11 terminates some distance short of the grate level and forms a substantially tubular open-ended magazine 14, by which fuel may be inserted into the fire chamber in the manner hereinafter described. The inner walls 5 of the main water leg 4 terminates short of the upper legs, as shown more clearly in Fig. 1. The upper end of the fire box is closed by a circular plate 15 centrally apertured, as shown at 16. To the plate 15 is secured by means of stay-bolts 16' an upper end-closure plate member 17, the outer edge of which is suitably bolted or riveted, as shown at 18, to the outer wall 6 of the main water leg. The upper plate 17 in conjunction with the plate 15 forms an upper water space 19, which extends over the entire upper end of the fire box and communicates with the respective vertical water legs 4 and 11. The upper plate 17 is centrally apertured to receive a feed trunk 20 which communicates with the upper end of the magazine 14 and is provided with a removable door or cap 21, whereby fuel may be inserted into the fire box. The arrangement just described is such that the side and the upper end of the fire box are entirely surrounded by water or boiler space and in addition the magazine 14 is inclosed by the water leg 11.

As a feature of the present construction, a relatively large number of water tubes 22

extend vertically throughout substantially the entire height of the fire box and communicate at their upper ends, as shown at 23, with the water space 19, and at their 5 lower ends with the water leg 4, as shown at 24. It will be noted that in the construction shown in Fig. 1 the lower ends of the tubes are open and curved outwardly in order that they may communicate with the water space 10 4. As shown in Fig. 2, these water tubes extend entirely around the fire chamber, the construction being such as to permit of the use of a relatively large number of such tubes in a minimum amount of space. The lower 15 inner water leg 11 may communicate with the outer water leg 4 by means of a plurality of pipes 11'. That part of the fire chamber which surrounds the inner water leg 11 may be termed an auxiliary combustion chamber, 20 designated as a whole 25, to the upper end of which is connected a stack or outlet pipe 26, which extends through the water leg 4, as shown more clearly in Fig. 1. The side wall of this stack is provided with ports 27, 25 to which are connected stub pipes 28 controlled by hinged closures 29, which are normally open. The main body of the pipe 26 may be also provided with a suitable damper 30, which is also normally closed. This 30 damper, however, is of slightly less diameter than the internal diameter of the pipe 26, so as to leave a restricted outlet passage even when the damper is in closed position. The arrangement is such that any pronounced 35 induced draft through the stack 26 is substantially eliminated. Inasmuch as the fuel is distilled, as contradistinguished from a direct burning, I provide means for introducing air to various parts of the fire zones. 40 To this end a plurality of stub pipes 31 lead from the ash pit directly into the lower part of the fuel body, and similar pipes 32 lead from the ash pit to the auxiliary combustion chamber 25. If desired, generally similar 45 pipes 33 carry air from the ash pit into the magazine 14. The arrangement is such that air is so supplied to the fuel and the draft so eliminated as to distil the fuel, and the gases of distillation are then ignited and 50 oxidized within the fire chamber.

The upper end of the water space 19 is provided with the usual steam dome 34, safety valve 35 and outlet pipe 36. Water may be fed to the boiler by means of an inlet 55 pipe 37 controlled by water cock 38. A conduit 39 extends through the lower end of the water leg and permits a poker to be inserted into the fuel body if desired. As many of these conduits may be provided as is found 60 necessary or desirable. Access may be had to the ash pit through a suitable door 40.

In Fig. 3 I have shown a slightly modified construction in which the water tubes are straight instead of being curved at their 65 lower ends, as heretofore described. Refer-

ring to this figure, the top of the ash pit 41 is provided with the usual grate 43. Upon the ash pit is supported the lower wall 44 of the boiler which is centrally provided with a trunk extension 45 leading to the fire 70 box proper. Upon this trunk is mounted a plate like ring 46 which forms the lower end of the combustion chamber. The inner wall 50 of the water leg 49 is supported on the plate ring 46 and the outer wall 48 thereof 75 extends to the ash pit. The two side walls of the main water leg are connected together by suitable staybolts or braces 57. The inner wall of the fire chamber is formed by the water leg 52 similar to that heretofore described, and forming a generally similar central fuel magazine 53, which communicates with the feed trunk 54, as shown. The upper end of the device is provided with closure plates 55 and 56 similar to the plates 80 15 and 17, heretofore described. It will be noted, however, that the main boiler or water space surrounds not only the side wall and upper end of the fire chamber, but the lower end as well. The fire chamber is similarly 90 provided with a series of circumferentially extending water tubes 57, which communicate with the upper and lower ends of the boiler, as shown.

Air is introduced to the lower end of the 95 fire box by means of pipes 58 leading from the ash pit, and in a similar manner air is supplied to the combustion space 59 of the fire chamber through open-ended pipes 60. If desired, air may also be supplied to the 100 central magazine 53 by means of a plurality of pipes 61 also leading from the ash pit. The modified construction just described secures a larger boiler surface, but slightly decreases the available fuel area of the fire box.

It is apparent that the fuel fills the central portion and lower end of the fire chamber, and that the gases of distillation will be oxidized in the combustion chamber. It is also to be noted that the various air pipes lead 105 from the ash pit or in other words at or below the grate level and accordingly the air, before it passes into the various parts of the fire zones, is preliminarily heated. In addition, the danger of the fire passing out 110 through the air portion when the draft is substantially eliminated, is obviated.

The invention is not limited to the details of construction shown, except as set forth in the appended claim.

I claim as my invention:

In a boiler, the combination of a main fire chamber, a fuel magazine extending vertically into said fire chamber and open only at its lower end and terminating short of the 125 grate level, air conduits leading from below grate level into the fuel on the grate, separated air conduits leading from below grate level to the combustion chamber adjacent the lower end of said fuel magazine, and 130

separate air conduits leading from below
grate level to the fuel magazine above the
fuel therein, the distilled gases from the fuel
in the magazine mixing with the air deliv-
ered to the magazine, the fuel magazine be-
ing devoid of any outlets except at its lower
end whereby the mixture of air and distilled

gases must pass downwardly through the
magazine and into and through the hot fire
adjacent the lower end of the magazine.

FRANCIS J. DOYLE.
